UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

LATHE.

SPECIFICATION forming part of Letters Patent No. 726,678, dated April 28, 1903.

Application filed May 3, 1902. Serial No. 105,839. (No model.)

To all whom it may concern:

Be it known that I, BENGT M. W. HANSON, a subject of the King of Sweden and Norway, residing at Hartford, in the county of Hartford 5 and State of Connecticut, have invented certain new and useful Improvements in Lathes, of which the following is a specification.

My invention relates to mechanism for stopping and reversing the carriage of a lathe or 10 other metal-working machine, and has for its object the provision of means for enabling the live-spindle to continue its rotary movement without actuating the train of gearing which imparts motion to the lead screw and 15 feed-rod when it is desired to perform the operations of filing or burnishing.

A further object of the invention is the provision of mechanism which will enable the work to be turned close up to a shoulder or 20 projection and yet will assure such limitation of the movement of the carriage that there will be no danger of breaking the tool carried in the slide-rest thereof.

A further object of the invention is the provision of mechanism adapted to stop the 25 movement of the carriage automatically in either direction, thereby obviating all danger of running the tool into the bottoms of holes in boring or internal thread-cutting.

30 A further object of the invention is the provision of a stopping and reversing mechanism for lathes which will enable duplicate parts to be accurately formed, therefore necessitating but one measurement for the kind of work being produced.

Other objects of the invention will be set forth in the detailed description which now follows.

In the accompanying drawings, Figure 1 is 40 a side elevation of a portion of a metal-working machine shown as a lathe with my improvements applied thereto. Fig. 2 is an end elevation of the same. Fig. 3 is a longitudinal vertical section of the head of a lathe having my improvement. Fig. 4 is a horizontal section of the bracket in which the shipper-rod is mounted. Fig. 5 is an end view of the shipper-fork shown in Fig. 3. Fig. 6 is an elevation, partially in section, of the mechanism for throwing the feed-gearing out of 45 action when it is desired to rotate the spin-

dle without reciprocating the carriage. Fig. 7 is a side elevation of one of the adjustable stop-carriers carried by the shipper-rod. Fig. 8 is a front elevation of said stop-carrier. 55 Fig. 9 is an elevation of the worm-gear and hand-wheel which give reciprocatory movement to the shipper-rod when it is desired to move the latter manually. Fig. 10 is an end view of an idler-pinion and a shiftable sleeve 60 embodied in the reversing mechanism. Fig. 11 is a detail view of the idler-pinion and its stud and the shiftable sleeve, a portion of the head being shown in section; and Fig. 12 is a perspective view of the clutch mechanism. 65

Like characters designate similar parts throughout the several views.

Referring to the drawings, the numeral 1 designates the bed or frame of the machine, having the shears 1' and the puppet-head 2 70 in the vertical standards 2', of which the back gearing A, cone or stepped pulley B, and live-spindle C, carrying face-plate D and center E are supported, all of these parts being of common construction, and therefore requiring no further description. 75

Designated by the numeral 5 is a carriage movable upon the shears 1' of the lathe-bed, said carriage having a depending portion 5', provided with a bearing 5², in which is journaled the shaft 6' of a hand-wheel 6, the inner end of said shaft carrying a worm-wheel 7, whose teeth engage a thread formed on the shipper-rod 9. 80

Depending from the bearing 5², carried by 85 the apron of the lathe-carriage, is a lug 10, and mounted on the shipper-rod 9, one at each side of said lug, are split carriers 12 12', respectively, each comprising a body portion 85, in the lower ends of which are fitted adjustable screws or stops 12², threaded into bearings 86 of said carriers and capable of being locked in position against displacement by lever-nuts 12³, as illustrated in Figs 1 and 8. As above stated, each of these carriers is 90 split, and the shipper-rod 9 passes through an opening located at the end of and communicating with the slot in the carrier, a screw a, having a handle b, being employed for drawing the split portions of the carrier together 95 and clamping the same upon the shipper-rod. This shipper-rod subserves a purpose herein- 100

after mentioned, is mounted at one end in a bracket 13, is slidably supported in a bearing (not shown) in a portion of the lathe-bed 1, and is recessed at 14 (see Fig. 4) for the reception of a plate 15, provided with V or other shaped notches 16 to receive the end of a spring-actuated plunger 18. The stem of this plunger is fitted in an opening of the bracket, and a spring 19, carried in a recess 20 of said bracket, bears against the head 18' thereof, a plug 21 being threaded into said recess and serving to alter the tension of the spring when necessary.

Designated by the numeral 22 is a rock-shaft which is journaled in a bearing 22' of the lathe-bed and is provided at its outer end with an arm 23, furcated at 23' for the reception of a pin 25, carried by the shipper-rod 9. At its inner end the rock-shaft is provided 20 with a vertical arm 26, furcated at 26' for the reception of a pin 27, carried by a sliding rod 28, mounted in a bracket 29 of the frame, said rod carrying at its opposite end a shipper-fork 30, the arms of said fork being provided with inwardly-projecting pins 30' 30'', Figs. 3 and 5, located in the space between a pair of collars 31 31' of the clutch-shifting rod for a purpose hereinafter described.

Coming now to the stopping and reversing mechanism employed, there is shown connected to the live-spindle C a gear-wheel 34, and at the outer end of said spindle is a gear-wheel 35 of smaller diameter, both of said gear-wheels being fast upon the spindle, 35 which is threaded at 36 for the reception of a split ring or collar 37, the latter being recessed at 37' to afford greater resiliency to said collar, which is designed to provide means for taking up lost motion of the spindle.

Located in a bearing 40 of the frame is a shiftable sleeve 41, in which are mounted the hubs of gear-wheels 42 and 43 of different diameters, the gear 42 being in mesh with the gear 34, while gear 43 engages an idler-pinion 44, which in turn intermeshes with the gear 35. Fitted in the hubs of the gear-wheels 42 and 43 is a shaft 45, having a collar 45' at one end and nuts 45'' at the opposite extremity, upon which is keyed at 46 the gear 47, which through a common train of gearing 48 (see Fig. 1) imparts motion to the lead-screw 49 and feed-rod 50 to reciprocate the carriage in the usual manner.

The shaft 45 is provided with a longitudinal bore for the reception of the clutch-shifting rod 51 and is slotted at 52 to permit said rod to be positively connected to a shiftable clutch 53 by a pin 54, said clutch being keyed or otherwise fastened to the shaft 45 60 and carrying single teeth 55 55', respectively, one upon each of its faces, the tooth 55 being designed to engage a similar tooth 56, carried upon the inner face of the hub of the gear-wheel 42, while the tooth 55' engages, 65 as shown in Fig. 3, a tooth 43', carried in like manner by the hub of the gear-wheel 43.

Mounted transversely of the bearing 40 is

a shaft 60, provided at its inner end with gear-teeth 61, which mesh with the teeth of a rack 62, formed upon the shiftable sleeve 70 41, said shaft being provided at its outer end with a crank 63, which is recessed at 64 for the reception of a spring-actuated plunger 65, carrying a knob 66, as best illustrated in Fig. 6, the lathe head-stock being provided 75 with a slot 67, in which the end of said plunger is designed to travel, recesses 68 for the reception of the plunger being provided at each end of the slot at the limit of stroke of said crank to secure it against accidental 80 movement.

The idler-pinion 44 is mounted for sliding movement upon a stud 69, carried by the frame, as illustrated in Figs. 3 and 11, said pinion being connected to the shiftable sleeve 85 41 through the medium of a pin 70, (see Figs. 3, 10, and 11,) the lower extremity of which is secured to said sleeve, while its upper end rests in a groove 71 of the hub of the pinion 44.

From the above description it will be seen that the live-spindle C may rotate continuously, and yet the proper reciprocatory feed movement will be imparted to the carriage on which the tool slide-rest is mounted.

In the embodiment of my invention illustrated the operation is as follows: When it is desired to employ the lathe for screw-cutting purposes, the clutch 53 is shifted to the left, and its single tooth 55' engages the like tooth 43' on the end of the hub of the gear-wheel 43. Power now being applied to the live-spindle by a belt engaging the desired stepped portion of the cone-pulley B, the gears 35 43 44 47 and the gear-train 48 are set in motion, and the feed-screw 49, which operates in the usual divided nut (not shown) of the lathe-carriage, will be turned to actuate said lathe-carriage and cause the cutter H, carried in the tool-post G of the slide-rest F to reciprocate longitudinally of the work at the speed determined by the element of the gear-train 48 in use. Before the thread-cutting operation commences the stop-carriers 12 and 12' are adjusted to such positions upon the shiftable rod 9 that when the carriage reaches the limit of movement toward the left to which it is desired to travel the lug 10 will come into contact with the stop 12' of the stop-carrier 12' and will shift the rod 9 to 110 the left and through the pin 25, arm 23, rock-shaft 22, arm 26, and pin 27 the sliding rod 28 to the right, the shipper-fork 30 acting when this is done to move the clutch-shifting rod 51, and consequently the clutch 53, also to 115 the right, thereby withdrawing the tooth 55' from contact with the tooth carried by the hub of the gear 43. When this has been accomplished, said gear will rotate idly upon the shaft 45 and consequently the clutch 53 120 being in a neutral position the motion of the lead screw will cease, although the spindle C will continue to rotate, the tool cutting a groove in the stock at the end of the thread.

If the thread being cut is a short one and it is desired to return the carriage by power through the medium of the lead-screw, the hand-wheel 6 is grasped and turned in such manner that the worm-gear 7, carried by the shaft 6', will by its rack-and-pinion engagement with rod 9 cause said rod to be shifted still farther to the left, which will, through the connections before described, shift the clutch 53 farther to the right and carry its tooth 55 into engagement with the tooth 56 upon the inner face of the hub of the gear-wheel 42. When this is done, the motion transmitted to the lead-screw through gear-wheel 34, gear-wheel 42, clutch 53, shaft 45, gear 47, and gear-train 48 will be to the left, or opposite to the motion transmitted to said lead-screw when the clutch is in engagement with the gear 43, and consequently the carriage will be returned to the right, the lug 10 acting against the stop 12² of stop-carrier 12 when the carriage has reached the end of its movement to cause the rod 9 to be shifted to the right, thereby moving the clutch 53 to the left, and thus disengaging it from the gear 42, which will then rotate idly without imparting motion to the shaft 45. At times it is desirable to return the carriage by hand through the medium of the wheel 80, the shaft 30 of which carries a pinion in engagement with the usual rack on the lathe-bed, said devices being common in machines of this character, and hence unnecessary to illustrate. Heretofore it has been necessary after a cut in forming a thread has been made and the carriage has been returned by hand preparatory to making another cut to stop the live-spindle and adjust the tool to the thread before the operation could be proceeded with; but by employing a clutch of the peculiar construction shown it is possible for the carriage to be started in its forward movement to cause the tool to make a second cut without stopping the spindle, and this result is achieved in the following manner:

As will be evident, a certain relation exists between the rate of speed at which the live-spindle C rotates and the rate of speed at which the carriage travels, this relation being varied by the gear speed train according to the pitch of the thread it is desired to form. Consequently if the clutch is automatically thrown out of engagement at the end of the forward movement of the carriage and the carriage is then returned by hand preparatory to the adjustment of the tool for a new cut it is obvious that if the clutch is again shifted to the left at a time when the thread being formed is not in position to receive the tool its single tooth will be in such position that it will not at once engage the single tooth on the hub of the gear-wheel 43, and therefore no movement of the carriage will follow until the stock is turned around far enough to insure its proper relation to the tool, because the clutch 53 and the shaft 45 have remained stationary while the carriage was be-

ing returned, and as the clutch, as above stated, carries but one tooth upon each of its faces that tooth retains a certain position, and when the tooth carried by the gear-wheel 43 comes to the position it held at the time the clutch was thrown out of engagement at the end of said forward movement of the carriage it engages the clutch and sets the feed mechanism in operation. In virtue of this construction it is therefore not necessary to stop the spindle when the carriage resumes its forward movement to make the succeeding cuts, for the clutch-tooth 55' being in the same position it follows that the spindle will also be in like position, and consequently the stock will receive the tool at the proper moment to continue the thread-forming operation. It is obvious that the forward movement of the carriage will cause the hand-wheel 6, through the engagement of the worm-gear carried by said wheel with the thread formed on the shiftable rod 9, to rotate continuously, and to prevent said rod from being shifted by the friction thus engendered the detent shown in Fig. 4 is employed, and from the description hereinbefore given it will be seen that said detent will act to hold the rod in position until positive movement is given the same by turning the hand-wheel with sufficient force to overcome the pressure of the spring 19 or by the action of the lug 10 against the stops 12² to accomplish the same result.

When filing or burnishing work, it is desirable that in order to reduce the noise and friction the train of gearing for rotating the lead-screw and feed-rod should remain stationary, and to accomplish this result the crank 63 is swung to the left in Fig. 1, the plunger 65 entering the recess 68 at the extreme left of the slot 67 to retain the crank in such position, said movement of the crank partially rotating the shaft 60, which will, through the pinion 61 meshing with the rack 62, cause the sleeve 41, gear-wheels 42 and 43, pin 70, and through said pin the idler-pinion 44 to be shifted to the left, (see Figs. 3 and 11,) which will throw said gear-wheels 42 and 43 out of mesh with the gear-wheels 34 and 35, and thus permit the spindle C to rotate without imparting motion to any of the mechanism excepting said gear-wheels 34 and 35. To permit this movement, the inner face of gear 42 is chambered at 42', and a recess 100 for the reception of said gear is formed in the head 2, as shown in Fig. 3.

When adjustment of the stop-carriers 12 and 12' is required, they are moved bodily upon the shiftable rod 9 until the approximate adjustment is secured and are then clamped in position by the screw a, after which a more exact adjustment is secured, if necessary, by the stop-screws 12², which are then locked against accidental movement by the lever lock-nuts 12³.

From the above description it will be seen that with a lathe provided with this improved

stopping and reversing mechanism it is possible to insure any desired limitation of the movement of the carriage when boring or in cutting internal screw-threads, thereby obviating all danger of breaking the tool by running into the bottoms of holes, and that in duplicating parts but one measurement is required, for after the stop-carriers 12 12' are once set to the desired adjustment the movement of the carriage is exactly the same each time it is fed forward, and consequently the tool will perform exactly the same work.

My invention is not limited to the exact construction shown and described, nor to the kind of gearing employed, or its precise proportionate relation, but includes within its purview other devices and modifications thereof capable of accomplishing the results set forth. Furthermore, the invention is not restricted to a metal-turning lathe, for it may be employed with other kinds of metal-working machines.

No claim is made to the details of the stopping and reversing mechanism of the live-spindle head, excepting as they coact in combination with other elements of the machine, such details being covered by my divisional application, Serial No. 117,285, filed July 28, 1902.

Having thus described my invention, what I claim is—

1. The combination, with a rotary spindle, of a tool-carriage; means for actuating said carriage; mechanism including a clutch for operating the carriage-actuating means; a shifting-rod; stops on said rod; means connecting said rod with the clutch; a manually-operated gear carried by the carriage and serving to actuate the shifting-rod; and means for preventing displacement of the shifting-rod by said gear as the carriage reciprocates.

2. The combination, with a carriage, and with mechanism for reciprocating the same, of a threaded rod for controlling said mechanism; adjustable stops carried by the rod; a device on the carriage for engaging the stops and shifting the rod; a gear on the carriage and in engagement with said rod; means for turning said gear; and means for preventing displacement of the rod by said gear when it rotates idly thereon.

3. The combination, with a tool-carriage, of a spindle; means, including a clutch, controlled by the spindle for reciprocating said

tool-carriage; a shifting-rod; means connecting said shifting-rod with the clutch; means controlled by the carriage for actuating said shifting-rod; a gear mounted in a bearing of the carriage and in engagement with said shifting-rod; and means for turning said gear and thereby actuating the shifting-rod, when it is desired to shift the clutch by hand.

4. The combination, with a carriage, and with means, including a clutch, for reciprocating said carriage, of a threaded rod carried by the frame; a gear-wheel, the shaft of which is journaled in the carriage, said gear-wheel being in engagement with the threaded rod; and a handle attached to the shaft of the gear-wheel.

5. The combination, with a movable carriage, of a shiftable rod, a gear on the carriage in engagement with said rod; means for actuating the gear and thus shifting the rod; a bracket in which a part of the rod is mounted; means carried by the bracket for preventing movement of the rod while the gear rotates upon it during the normal movements of the carriage; and carriage-operating mechanism controlled by the rod.

6. The combination, with a carriage, of a shiftable rod; a wheel on the carriage normally rotating idly on the rod; means for normally preventing displacement of the rod by said wheel; means for actuating the wheel when it is desired to shift the rod; a clutch; means actuated by the rod for shifting said clutch; a spindle; and mechanism driven from the spindle, and including said clutch, for actuating the carriage.

7. The combination, with a traveling carriage, of a shaft journaled in a bearing of said carriage; a worm-wheel carried on the inner end of said shaft; a hand appliance on the outer end of said shaft; a threaded rod with which said worm-wheel is in engagement; a notched plate secured to the end of said rod; a bracket in which the end of the rod is mounted; a spring-actuated detent carried by the bracket; and carriage-operating mechanism controlled by said rod.

In testimony whereof I affix my signature in presence of two witnesses.

BENGT M. W. HANSON.
